UNITED STATES PATENT OFFICE.

PHILIPP SCHLACHTER, SR., AND ALONZO W. ALLEN, OF STREATOR, ILLINOIS, ASSIGNEES OF ONE-THIRD TO PHILLIP SCHLACHTER, JR., OF STREATOR, ILLINOIS.

DRAWING BOARD AND APPLIANCES.

SPECIFICATION forming part of Letters Patent No. 707,165, dated August 19, 1902.

Application filed February 11, 1902. Serial No. 93,585. (No model.)

To all whom it may concern:

Be it known that we, PHILIPP SCHLACHTER, Sr., and ALONZO W. ALLEN, citizens of the United States, residing at Streator, in the 5 county of LaSalle and State of Illinois, have invented new and useful Improvements in Drawing Boards and Appliances, of which the following is a specification.

Our invention relates to improvements in 10 drawing boards and appliances, and has for its object to provide means calculated when used in conjunction with an ordinary triangle to materially facilitate the drawing of true horizontal and perpendicular lines.

15 With the foregoing in mind the invention will be fully understood from the following description and claims when taken in conjunction with the accompanying drawings, in which—

20 Figure 1 is a plan view of a drawing-board equipped with our improvements; Figs. 2 and 3, enlarged detail sections taken in the planes indicated by the lines 2 2 and 3 3, respectively, of Fig. 1; and Fig. 4, a plan view 25 of the spring forming part of the improvements removed, and Fig. 5 a detail of a modification.

Similar letters of reference designate corresponding parts in all the views of the drawings, referring to which—

30 A is a drawing-board, which is peculiar, in that it has a groove or way *a* adjacent to one edge and a straight edge *b* overhanging the way or groove. We prefer to form the groove 35 in a strip of wood *c*, attached by screws *d* to the edge of the board, and to have a strip of steel, attached to strip *c* by screws *e*, constitute the straight edge. This construction is preferable, because it adapts the improvements to be applied with facility to drawing-boards and the tops of drawing-tables, such 40 as at present in use.

B is a slide movable on the board A. This slide preferably comprises a bar *g*, a head *f*, 45 of greater thickness than the bar, so as to extend above and below the same, and a brace *g'*, corresponding in thickness to the bar *g* and interposed between the same and the head *f*. The head *f* is preferably provided 50 at its ends with bifurcations in which ends

of the bar *g* and brace *g'* are secured by glue or other means, and the opposite end of the brace *g'* is connected to the bar *g* by glue or other means. Said head *f* is arranged parallel to and adapted to engage the straight edge *b* after the manner best shown in Fig. 2, while the bar *g* is preferably arranged at an angle of forty-five degrees to the head and is of a length to reach across the board A, as shown.

55 C is a spring, which preferably comprises an intermediate loop *h*, let into a recess *i* in the inner side of the head *f* of slide B, and arms *j*, extending in opposite directions from the loop and terminating in hooks *k*, disposed in the groove *a* and engaging the under side of the inner portion of the straight edge *b*, and D is a pin removably arranged in coincident apertures *l* of the slide-head *f* and extending through the loop *h* of spring C.

60 When the slide B rests on the board A with its head *f* in engagement with the straight edge *b* and the spring C is connected to said head of the slide by the pin D and rests with its hooks *k* in the groove *a* and in engagement with the straight edge *b*, as best shown in Figs. 2 and 3, it will be observed that the spring will operate to yieldingly press the head *f* against the straight edge *b* and thereby hold the slide B to and against casual 65 movement on the board, and this without preventing or rendering difficult the necessary adjustment of the slide along the board by the draftsman.

70 In practice when it is desired to draw horizontal lines an ordinary triangle is placed and held against the edge of the bar *g*, as shown by the lower dotted lines in Fig. 1, while when it is desired to draw vertical lines the triangle is placed and held against the 75 edge of bar *g*, as shown by the upper dotted lines in said figure. From this it follows that our improvements when used in conjunction with an ordinary triangle are calculated to enable a draftsman to make horizontal and vertical lines with great ease and quickness.

80 When it is desired to work the triangle at the right of the slide B instead of at the left thereof, the slide is reversed—i. e., the pin D 85

90

95

100

is removed, the slide is drawn out of engagement with the loop of spring C and turned over and placed again in engagement with the loop of the spring, and the pin is replaced 5 in the slide and spring-loop. From this it will be appreciated that the reversal of the slide does not entail the disconnection of the spring from the board, and hence may be quickly and easily accomplished.

10 We have entered into a detailed description of the construction and relative arrangement of parts embraced in the present and preferred embodiment of our invention in order to impart a full, clear, and exact understanding 15 of the same. We do not desire, however, to be understood as confining ourselves to such specific construction and arrangement of parts, as such changes or modifications may be made in practice as fairly fall within the 20 scope of our claims.

25 The strip c', Fig. 5, is hinged at each end of the board and is provided with a pin b² for the engagement of a hook b³, by means of which it is normally held in the position shown by full lines. When the strip c' is released from the fastener and swung into the position shown by dotted lines in Fig. 5, paper, such as used for large drawings and map-work, may be passed between the strip and 30 board, and the surplus of such paper may be rolled up underneath the table.

Having described our invention, what we claim is—

1. The combination of a drawing-board 35 having a groove and a portion overhanging said groove, a slide arranged on the board and having a head bearing against one edge of the portion overhanging said groove, and a spring connected to the head of the slide 40 and having a portion arranged below and in engagement with the portion of the board which overhangs the groove so as to hold the slide down on the board.

2. The combination of a drawing-board

having a groove and a portion overhanging 45 the same, a slide arranged on the board and having a head bearing against one edge of the portion overhanging said groove, and a spring connected at an intermediate point of its length to the head of the slide, and having oppositely-extending arms disposed in the groove of the board and terminating in hooks engaging the portion of the board which overhangs said groove. 50

3. The combination of a drawing-board 55 having a groove and a portion overhanging the same, a slide arranged on the board and having a head bearing against one edge of the portion overhanging said groove, and also having a recess in the inner side of the head, 60 and an aperture intersecting said recess, a spring having a loop disposed in the recess of the slide-head, and arms extending in opposite directions from the loop and disposed in the groove of the board and terminating 65 in hooks engaging the portion of the board which overhangs the groove, and a removable pin resting in the aperture of the slide-head and the loop of the spring. 70

4. An attachment for drawing-boards comprising a strip having a groove, a straight edge connected to the strip and overhanging the groove thereof, a slide having a head bearing against the straight edge, and a spring connected at an intermediate point of its 75 length to the head of the slide and having oppositely-extending arms disposed in the groove of the strip and terminating in hooks engaging the portion of the straight edge which overhangs said groove. 80

In testimony whereof we have hereunto set our hands in presence of two subscribing witnesses.

PHILIPP SCHLACHTER, SR.
ALONZO W. ALLEN.
